A. K. MILLER,
PHONOGRAPH REPRODUCER.
FILED FEB. 18, 1920.

Inventor:
Alfred K. Miller,

his Attorney.

UNITED STATES PATENT OFFICE.

ALFRED K. MILLER, OF LOS ANGELES, CALIFORNIA.

PHONOGRAPH REPRODUCER.

Application filed February 18, 1920. Serial No. 359,725.

To all whom it may concern:

Be it known that I, ALFRED K. MILLER, a citizen of the United States, residing at Los Angeles, in the county of Los Angeles, State 5 of California, have invented new and useful Improvements in Phonograph Reproducers, of which the following is a specification.

This invention relates generally to sound-boxes, being more specifically designed to be 10 used as a phonograph reproducer; but without necessarily being limited to use specifically as a phonograph reproducer. It will be readily understood, after a perusal of the following description, that the device may 15 be used wherever sound-boxes are used for the purpose of transforming mechanical vibrations into sound vibrations.

For simplicity and clarity of description I shall describe my device in its specific 20 form as designed for a phonograph reproducer; stating the objects and accomplishments of the invention specifically as regarding that form of my device, without at all intending that such description, and 25 statement of the objects and features of the invention, shall limit my invention specifically or entirely to phonograph reproducers. As applied to phonograph reproducers, it is an object of the present invention to provide 30 a sound-box which will give improved reproductive results. The general objects of the invention are set forth in my previous application Serial No. 316,039, filed Aug. 8, 1919; and my present invention includes 35 improvements upon the sound-box set forth in my previous application, the present improvements being along the line of purer tone production of greater clarity; the production of overtone qualities; and, in fact, 40 (as applied to a reproducer) reproduction of all the proper tone qualities which are in a phonograph record, and to a certain extent at least, the damping out or elimination of sounds which, although in the 45 phonograph record, are undesirable; and the damping out or minimizing of the undesirable sounds arising from the characteristic vibration of the needle-vibrated diaphragm itself.

50 A further and more particular object of the present invention is to provide a phonograph reproducer construction which will accomplish the general objects of this invention, and which may be easily made with

comparatively little expense and present a 55 pleasing exterior appearance.

As between this present application and the prior one referred to the broader and common subject matter is herein claimed; the claims of the prior application being 60 limited to the specific forms therein shown and not shown herein.

The various objects, and corresponding features, of my invention in its form as specifically applied to phonograph reproducers, will be better and more fully understood from the following detailed description, reference for this purpose being had to the accompanying drawings in which I show in detail a phonograph reproducer made in 70 accordance with my invention. In these drawings Fig. 1 is a rear face elevation of my improved reproducer; Fig. 2 is a front face elevation of the same; Fig. 3 is a side elevation taken as indicated by line 3—3 on 75 Fig. 1; Fig. 4 is a side elevation taken as indicated by line 4—4 on Fig. 1; Fig. 5 is an enlarged section taken as indicated by line 5—5 on Fig. 1; Fig. 6 is an enlarged fragmentary face elevation taken as indicated by line 6—6 on Fig. 5; Fig. 7 is a side elevation of the part shown in Fig. 6; and Fig. 8 is a detail section taken as indicated by line 8—8 on Fig. 6.

In the drawings the numeral 10 designates 85 the body of a case having an exterior flange 11 and an interior flange 12. The case is formed of the body member 10 and of a case member 13 which has an exterior flange 14 and an interior flange 15. 90 The case fits over the body 10 and its flange 14 fits against flange 11 of the body member. Flange 11 of the body member is on that face of the sound-box which I designate the rear face; and on this rear face there 95 is a flange or flat ring 16 secured by screws 17 to flange 11; the screws 17 also serving to secure flange 14 against flange 11.

On the front face of the case there is a flat ring or flange 18 secured by screws 19 100 to flange 15 of case member 13. Flange 15 has around its inner edge an annular recess 20 and one of the secondary resonating diaphragms is held in this recess by the flange 18.

The foregoing described construction is, in detail, the case which I now specifically prefer for my specific preferred arrange-

ment of vibrating diaphragms which I will now proceed to describe. I shall also herein-after state the materials of which I prefer to make the various parts of the device, and 5 shall also, in order to give a complete and clear idea of a specific and successful form of my invention, give the characteristic dimensions of the parts as herein set forth. It will, however, be readily understood, that 10 I give all of these details for the purpose of rendering my invention, in one of its forms, clear and intelligible and capable of being practically understood by those skilled in the art, rather than for the purpose of 15 necessarily limiting my invention to these particular details.

In the specific embodiment of my invention now to be described, I employ a primary diaphragm to which is connected the phonograph needle; and two secondary resonating diaphragms of certain characteristics and of certain relative arrangement to be explained. The primary diaphragm 25 may 20 be preferably a mica diaphragm, or of any suitable material, and the circular edge of this diaphragm is mounted in a rubber (preferably soft rubber) mounting ring 26 which encircles its edge and lies on both edge faces of the diaphragm. This is 25 clearly illustrated in the drawing. Such a mounting ring may readily be made by slightly stretching a rubber band of appropriate circumference and bending the edges of the rubber band over the edge faces of 30 the diaphragm. It is thick enough, and of sufficiently yielding qualities, to effectually prevent the vibrations of diaphragm 25 reaching the case in any great degree. The inertia of the case also assists in minimizing 35 its vibration, either by the needle mounting or from the primary diaphragm. The vibrations of the case being thus minimized, it is easier to insulate the secondary diaphragms from vibration. This rubber 40 mounting ring rests against the interior flange 12 of case body 10; and is held in place by the edge of secondary diaphragm 27 which in turn is held in place by the flange 16, with a rubber ring 28 and a 45 paper ring 29 interposed between the flange and the edge of the secondary diaphragm. The paper ring is a filler; and by changing its thickness—as for instance, putting in 50 more or less thin paper rings—the holding pressure on the rubber rings and on the diaphragms may be adjusted to a nicety. This secondary diaphragm 27 is, in this present specific embodiment and arrangement of my invention, composed of what is ordinarily 55 known as hard nickel silver. It is here two one-hundredths of an inch in thickness. Near its edge it has a bend 30 extending on a circular line clear around it, so that its edge portion 31 is somewhat offset from the main 60 central portion of the diaphragm; so that 65

the effective vibrating portion of the diaphragm is more or less delimited at the circular bend 31. This circular bend is at such a diameter as to make the effective vibrating part of diaphragm 27 of about the same 70 diameter as the effective vibrating part of primary diaphragm 25. The rubber mountings for these two diaphragms are compressed sufficiently by the flange 16 to hold the diaphragm securely in place; but the rubber 75 mountings are not compressed to the extent that vibrations from one diaphragm will pass to the other through the case or directly through the rubber mounting 26. The secondary diaphragm is, as far as possible, left free to vibrate in its own characteristic mode of vibration, without being forced by vibrations which might otherwise reach it through the mountings or through the case from the primary diaphragm 25, or 80 which might reach it from the case itself which is more or less set in vibration by the vibration of the needle and needle arm mounted on the case. The form of mounting 26 prevents the edge of primary diaphragm 25 touching the case; and the bend at 31 in secondary diaphragm 27 centers that diaphragm on mounting 26 and prevents its edge coming in contact with the case. The two diaphragms are thus mounted 85 solely on their rubber mounting rings and do not contact with the case at any point.

Secondary diaphragm 27 has at its center an aperture surrounded by a nipple 31^a 100 preferably integral with the diaphragm itself. This nipple 31^a is of such size as to be adapted to fit over a sound arm 32, being provided with a pin 33 which engages with slot 34 in the sound arm, for locking the nipple upon the sound arm. It is through the medium of this nipple and through the medium of the secondary diaphragm 27 that the whole sound-box is supported and mounted upon the sound arm 32; that is, 105 the diaphragm 27 becomes itself an element in the support and mounting for the whole sound-box.

The other secondary resonating diaphragm 35 is formed as the bottom of a 115 cup-shaped diaphragm and chamber member 36 which has a circular and slightly conical sidewall 37 and a rim flange 38 held in a rubber mounting member 39 in annular recess 20 and under the flange 18. Rubber 120 mounting member 39 is similar to the mounting member 26 except that it may be smaller. It will be noted that the external diameter of rim flange 38 is such that the rubber mounting member does not touch the outer 125 circumferential wall of the annular recess 20; and the inner edge of flange 18 does not touch the side wall 37 of the diaphragm member 36; so that the diaphragm member is solely and entirely mounted in the case 130

through the intervention of the rubber mounting member 39. This rubber mounting member is only clamped tightly enough to hold the diaphragm and chamber member 36 in place, without compressing the rubber to such a degree as to transmit vibration to the diaphragm member from the case. This rubber ring 39, as well as the others, 26 and 28, is air-tight. The rubber mountings prevent air leakage around the diaphragm edges to and from the resonating chamber, or chambers. It will be understood that the space between diaphragms 25 and 27 may, of itself, or with the sound arm 32, form a resonating chamber conforming in vibration characteristics with the diaphragm 27. The cup-shaped member 36 is preferably pressed out of the same material as diaphragm 27, and the thickness 20 of this material, and the thickness of diaphragm 35, is one one-hundredth of an inch. The diameter of diaphragm 35, it will be noted, is substantially less than the diameter of diaphragm 25. The fact that 25 diaphragm 35 forms the bottom of the cup-shaped member 36 places diaphragm 35 at a distance from primary diaphragm 25; the case of the device and the member 36, together with diaphragms 25 and 35, 30 enclosing a resonating chamber whose resonant vibration characteristics are preferably in correspondence with the resonant vibration characteristics of diaphragm 35. Using secondary diaphragms of the material 35 and of the thicknesses here stated, I find that I attain very satisfactory results when the diameter of diaphragm 35 is about one and three-eighths inches; the total diameter, from edge to edge, of diaphragm 25 is about one and seven-eighths inches; the distance between diaphragms 25 and 35 is about five-eighths of an inch; the effective vibratory diameter of secondary diaphragm 27 is about one and three-fourths inches; and the distance between diaphragms 25 and 27 is about three-sixty-fourths of an inch at their edges. At their centers these diaphragms may be somewhat further apart due to the normal flexing of 45 the primary diaphragm toward the left in Fig. 5.

I find that if I make the case and its parts, of brass, I have a reproducer that gives about the proper weight on the needle. All 55 of the exteriorly appearing parts, with the exception of the two secondary diaphragms, may be plated or otherwise finished. The interior surfaces of the various case parts are preferably smooth finished.

60 The foregoing specifies an arrangement and design that I find to give very good results. I have chosen these dimensions and arrangements after long experiment with a view to arriving at the best sound production 65 and the elimination of undesirable sounds.

I find that the secondary diaphragms and the resonating chamber, or chambers, selectively resonate the primary diaphragm vibrations so as to bring out tone qualities that are ordinarily lost in reproduction. 70 The vibration characteristics of the secondary diaphragms are purposely different from those of the primary, and also preferably different from each other; and it is in this difference—the selective resonance—that my 75 good results are made, resulting in the resonance of tones that otherwise are feeble or drowned out, and the damping off of sounds that are undesired.

Using my device as a sound reproducer, 80 it is necessary to provide a means for vibrating the primary diaphragm 25 from a record following needle. The record following needle is secured in the needle-holding head 40 in the usual manner. Head 40 has two 85 lateral extensions 41 provided with grooves 42 which rest on knife-edges 43. Each extension 41 has a transverse pin 44; and each pin is pressed upon by the bifurcated ends 45 of a spring 46. Spring 46 is a curved 90 flat spring whose end is held in a notch at 47; and the tension of the spring ends 45 on pins 44 is adjusted by screws 48. It will be noted that the tension of springs 46 holds the parts 41 in engagement with knife 95 edges 43; and at the same time a spring tension is applied equally to opposite sides of the vibratory axis of the system; the bifurcations 45 of each spring pressing equally upon the opposite ends of each pin 100 44. Consequently, when an adjustment of the screws is made to adjust the spring tension, no substantial change is made in the position of diaphragm 25, there being no 105 tendency on the part of the springs, when adjusted to more or less tension, to throw the diaphragm into more or less than normal tension either side of its normal central position of rest. The parts are arranged so that the diaphragm normally stands flexed 110 somewhat forwardly.

The needle head 40 has an extension 50 which carries the needle arm 51. Needle arm 51 projects into the interior of the case, through the wall of member 13, and is 115 connected with the center of primary diaphragm 25, in any of the well known manners. A small aperture at 52 allows the passage of the needle arm into the interior of the case. The needle arm of course does 120 not fit the aperture tightly, allowing room enough for the needle arm to vibrate; but the looseness around the needle arm does not materially alter the substantially enclosed condition of the resonating chamber inside 125 the case. It simply provides that small opening which, under any circumstances, would be required to the exterior atmosphere to keep atmospheric pressure equalized inside and outside the resonating chamber. 130

Having described a preferred form of my invention, I claim:

1. In a sound box, a case, a primary diaphragm therein, and a plurality of secondary diaphragms therein in spaced and resonant relation to the primary diaphragm, each secondary diaphragm having vibration characteristics different from the others and from the primary diaphragm. 70
2. In a sound box, a case, a primary diaphragm therein, and two secondary diaphragms therein in spaced and resonant relation to the primary diaphragm, one on each side of the primary diaphragm, each secondary diaphragm having vibration characteristics different from the other and from the primary diaphragm. 75
3. In a sound box, a case, a primary diaphragm therein, and two secondary diaphragms therein in spaced and resonant relation to the primary diaphragm, one of the secondary diaphragms being relatively thin and far-spaced from the primary diaphragm and the other being relatively thick and close-spaced to the primary diaphragm. 80
4. In a sound box, a case, a primary diaphragm therein, and two secondary diaphragms therein in spaced and resonant relation to the primary diaphragm, one of the secondary diaphragms being of lesser diameter than the primary diaphragm, and each secondary diaphragm having vibration characteristics different from the other and from the primary diaphragm. 85
5. In a sound box, a case, a primary diaphragm therein, and a plurality of secondary diaphragms therein in spaced and resonant relation to the primary diaphragm, one on each side of the primary diaphragm, one of the secondary diaphragms being relatively thin and far-spaced from the primary diaphragm and the other being relatively thick and close-spaced to the primary diaphragm, the thin far-spaced diaphragm being of lesser diameter than the primary diaphragm, and the relatively thick, far-spaced, diaphragm having an opening, and a sound tube leading from the opening in said diaphragm. 90
6. In a sound box, a case, and vibratory diaphragm means therein embodying an apertured vibratable diaphragm having mounting means around its aperture adapted to be connected to a sound tube and forming the supporting mounting for the sound box. 95
7. In a sound box, a case, a primary diaphragm in the case, a secondary diaphragm in the case in resonating relation to the primary diaphragm, the secondary diaphragm having an opening and mounting means around the opening adapted to engage a sound tube. 100
8. In a sound box, a case, a primary diaphragm therein, and two secondary diaphragms therein in spaced and resonant relation to the primary diaphragm, one of the diaphragms being imperforate and the other having an opening and a sound tube leading from the opening in said diaphragm, the vibration characteristics of each secondary diaphragm being different from each other and from the primary diaphragm. 105
9. In a sound box, a case, a primary diaphragm therein, and a plurality of secondary diaphragms therein in spaced and resonant relation to the primary diaphragm, one on each side of the primary diaphragm, one of the secondary diaphragms being relatively thin and far-spaced from the primary diaphragm and the other being relatively thick and close-spaced to the primary diaphragm, the relatively thick, far-spaced, diaphragm having an opening, and a sound tube leading from the opening in said diaphragm. 110
10. In a sound box, a case, a primary diaphragm therein, and a plurality of secondary diaphragms therein in spaced and resonant relation to the primary diaphragm, one on each side of the primary diaphragm, one of the secondary diaphragms being relatively thin and far-spaced from the primary diaphragm and the other being relatively thick and close-spaced to the primary diaphragm, the thin far-spaced, diaphragm being of lesser diameter than the primary diaphragm, and the relatively thick, far-spaced, diaphragm having an opening, and a sound tube leading from the opening in said diaphragm. 115
11. In a sound box, a case, a primary diaphragm therein, a plurality of secondary diaphragms therein in spaced resonant relation to the primary diaphragm, each of said secondary diaphragms having vibration characteristics different from those of the primary diaphragm and from each other; one of said secondary diaphragms enclosing between it and the primary diaphragm a resonating chamber, and the resonant vibration characteristics of the chamber being in correspondence with those of said secondary diaphragm. 120
12. In a sound box, a case, a primary diaphragm therein, a pair of secondary diaphragms in the case one on each side of the primary diaphragm, each of the secondary diaphragms having vibration characteristics different from those of the primary diaphragm and from each other, one of the secondary diaphragms being imperforate, the other being apertured and adapted for connection with a sound tube, the imperforate diaphragm being relatively thin and enclosing a resonating chamber between it and the primary diaphragm, and the apertured diaphragm being relatively thick. 125
13. In a sound box, a case, a primary diaphragm of mica, a cup-shaped member having a rim and an integral flat diaphragm bottom of nickel silver constituting a secondary diaphragm, the member being mounted by its 130

rim in the case with its diaphragm bottom in resonant relation to the primary diaphragm.

14. In a sound box, a case, a primary diaphragm therein of mica, a cup-shaped member having a rim and an integral flat diaphragm bottom of nickel silver constituting a secondary diaphragm, the member being mounted by its rim in the case with its diaphragm bottom in resonant relation to the primary diaphragm; and the case, the cup-shaped member and the primary diaphragm enclosing a resonating chamber whose vibration characteristics correspond to those of the secondary diaphragm.

15. In a sound box, a case, a primary diaphragm in the case, and two secondary diaphragms therein, the secondary diaphragms being mounted in such relation to the primary diaphragm and being of such material and dimensions as to be resonantly vibrated from the primary diaphragm, and the vibration characteristics of the two secondary diaphragms being different from each other.

20 16. In a sound box, a case, a primary diaphragm therein, a secondary diaphragm in the case at one side of the primary diaphragm and in resonant relation to the primary diaphragm; and a resonating chamber 25 at the other side of the primary diaphragm, the vibration characteristics of the primary diaphragm and of the secondary diaphragm and of the chamber each being different from each of the others.

30 35. 17. A sound box, embodying a case, primary and secondary diaphragms therein, the secondary diaphragm being in resonant rela-

tion to the primary diaphragm and having vibration characteristics different from those of the primary diaphragm so that the secondary diaphragm selectively resonates the vibrations of the primary diaphragm. 40

18. A sound box, embodying a case, and primary and secondary diaphragms therein, the primary diaphragm being of mica, and the secondary diaphragm of nickel silver, and the secondary diaphragm being in resonant relation to the primary diaphragm so as to selectively resonate its vibration. 45

19. A sound box, embodying a case, a diaphragm therein, and a resonating element in resonant relation to the diaphragm, said resonating element having vibration characteristics such as to be resonantly vibrated from the diaphragm but having its vibration 50 characteristics somewhat different from those of the diaphragm so that said element selectively resonates the diaphragm. 55

20. A sound box, embodying a case, a diaphragm therein, and a resonating chamber 60 in resonant relation to the diaphragm, said resonating chamber having vibration characteristics such as to be resonantly vibrated from the diaphragm but having its vibration 65 characteristics somewhat different from those of the diaphragm so that said chamber selectively resonates the diaphragm.

In witness that I claim the foregoing I have hereunto subscribed my name this 2d day of February, 1920.

ALFRED K. MILLER.
